DESIGN.

No. 30,706.

Patented May 2, 1899.

W. T. BOYD.

BOX BLANK.

(Application filed Mar. 14, 1899.)

UNITED STATES PATENT OFFICE.

WILLIAM THEODORE BOYD, OF PITTSBURG, PENNSYLVANIA.

DESIGN FOR A BOX-BLANK.

SPECIFICATION forming part of Design No. 30,706, dated May 2, 1899.

Application filed March 14, 1899. Serial No. 709,095. Term of patent 14 years.

To all whom it may concern:

Be it known that I, WILLIAM THEODORE BOYD, a citizen of the United States, residing in Pittsburg, Pennsylvania, have invented 5 and produced a new and original Design for a Box-Blank, of which the following is a specification, reference being had to the accompanying drawing.

In the drawing the figure represents the box-blank with the folds spread out horizontally.

The leading feature of my invention is in the shape and configuration of the blank from which the box is folded up. This blank is perfectly flat and has parallel edges a a , these 15 edges extending out obliquely at i and k and then running parallel again, as at g h , and

then extending inwardly obliquely, as at l m , the oblique lines l m being connected by a straight line n . The blank is creased so as to be folded, and the creases form panels b , c , d , e , and f , the portions outside of these panels constituting the ends of the box.

What I claim is—

The design for a box-blank as herein shown and described.

In testimony whereof I affix my signature in presence of two witnesses.

WM. THEODORE BOYD.

Witnesses:

JOHN L. WILSON,
A. D. WILSON.
